TRAIN CONTROL

Filed June 28, 1924

UNITED STATES PATENT OFFICE

CHARLES S. BUSHNELL, OF ROCHESTER, NEW YORK, ASSIGNOR TO GENERAL RAILWAY SIGNAL COMPANY, OF ROCHESTER, NEW YORK

TRAIN CONTROL

Application filed June 28, 1924. Serial No. 723,048.

This invention relates to automatic train control systems, and more particularly to systems commonly known as the continuous inductive train control type.

5 This type of train control system usually employs alternating control currents flowing in the track rails and inductively transmitted from the track rails to suitable receiving devices located on the locomotive or other moving vehicle, and these currents act on suitable 55 car-carried apparatus to control the progress of the train in accordance with changes in traffic conditions ahead, as manifested by changes in the track rail control currents.

10 In applying this type of train control system to existing railway systems, it becomes necessary to provide for the operation of trains equipped for automatic train control over sections of trackway not equipped for 15 train control operation. It is essential to safe train operation that this change of condition of the train or car-carried control apparatus, releasing the train from automatic control, should be made only at points at 20 which the train enters unequipped territory. It is evident that if a mere manual actuation 25 of a switch, lever or other means were used to effect this change, the engineer or train operator could at any time in equipped territory 30 release the train from automatic train control and so proceed with no annoying restrictions as to speed.

35 It is one object of this invention to provide a simple and efficient automatic means for releasing the train from one action of the automatic control apparatus at the point where such train enters an unequipped section of trackway, and for again placing the train under the restrictions of the automatic control apparatus when a section of trackway 40 equipped for train control is encountered.

45 The control apparatus is usually reset to its active condition by means of the return of the control current which flows in the track rails in equipped sections of trackway. It has been found in practice that at certain points along a section of trackway not equipped for train control, stray currents sometimes flow for short distances in the 50 track rails. These stray currents or tran-

sients, as they are sometimes called, may be caused by the leakage of alternating signal currents from adjacent track rails to the track rails under consideration, or they may arise from other causes. The effect of these 55 stray currents, which are usually of short duration in point of train travel, is to reset the car-carried train controlling apparatus to its active condition, and thereby to impose an immediate restriction on the train speed, 60 usually bringing the train to a stop, slowing up traffic, and causing unnecessary delays and inconvenience.

65 It is a further object of this invention to provide car-carried means which will act to prevent the resetting of the car-carried control apparatus to its active condition until a certain interval of train travel has elapsed from the point at which a current influence is received from the track rails. By requiring such a distance of travel to reset the control apparatus, such resetting of the control apparatus and subsequent delay in train 70 operation due to stray currents flowing over short lengths of the track rails will be avoided, and more efficient train operation will 75 result.

75 Other objects, advantages and desirable features of the invention will be pointed out or will become apparent as the description 80 of the system progresses.

85 In the drawings, a section of trackway and the car-carried apparatus equipped for a train control system embodying the present invention has been represented in a conventional and simplified manner.

90 Referring particularly to the trackway equipment in the territory equipped for the regular automatic train control, the track rails 1 are divided into blocks by the insulating joints 2; the block I and portions of the adjacent blocks II and J, having been shown. The normal direction of train travel along the trackway is indicated by the arrow.

95 Track signal and train control currents are impressed across the rails at the exit end of each block by means of the track battery 3 and the secondary winding of the transformer 4 as shown. The primary winding of this transformer is energized through the 100

contact fingers 5 and 6 of the track relay 7 and the transformer 8 which is connected across the transmission line 9 as clearly shown in the drawings. The track relay 7 is connected across the track rails 1 at the entrance end of each block by the wires 10 and 11. This track relay 7 may be of any suitable type, but in the specific embodiment shown is preferably of the direct current type.

10 Wayside signals of the semaphore, light signal or any other suitable type, operated by the track relay 7, may or may not be used. For the purpose of illustration, semaphore signals Z of the type common in railway signal practice have been conventionally shown at the entrance end of each block. The means for operating these semaphore signals from the track relays 7 have not been illustrated as these means are clearly understood by those skilled in the art, and as these means form no part of the present invention.

15 That portion of the trackway which is not equipped for automatic train control is conventionally illustrated and referred to as non-control territory, and may be a siding, a branch line, a portion of the main line trackway, or the like. This non-control territory may or may not be equipped with track circuits and block signals; but as shown in 20 the drawings, the non-control territory, comprising the block K is assumed to be equipped with the usual track relays, assumed to be of the direct current type, and with semaphore block signals.

25 35 At the entrance of the non-control territory, special trackway equipment is required to set the car-carried apparatus to its non-control condition. In accordance with this invention an excess amount of current is supplied to the track rails, or to a wave wire or loop adjacent to the track rails and producing a flux field in the same direction as that of a field produced by current flowing 40 in the track rails, at a point on the trackway where the change from train control to non-train control territory is made. As shown, a short section of the track rails J, adjacent to the non-control territory is provided, this section being hereinafter referred 45 to as the excess energy section. An alternating train control current of the same frequency as that used in blocks H and I, but of an appreciably higher voltage, is supplied to the track rails of this excess energy section so that considerably more current will flow in the rails in section J than in the rails of blocks H and I. This current in section J is supplied to the rails at the exit end of the section by the secondary winding of 50 the transformer 18, whose primary winding is energized from the transmission line 9.

55 In train control territory, the presence of a train in a given block cuts off the train control current behind the train in that block and in the next block in the rear. In order

that the train control current in the block I may reflect traffic conditions, and may be dependent on the presence or absence of a train in the excess energy section J or in the block K, it is proposed to provide the excess energy section J with a track relay 16, and the block K immediately ahead with a track relay X, the two sections J and K being preferably at least as long as safe braking distance for a train running at speed. With a train in either block K or section J, the line relay 14 will be deenergized, cutting off the train control current from the block I, and thus making this a caution block.

60 A railway vehicle has been conventionally represented by the wheels and axles 19 in the block H. In front of the leading axles, over and in inductive relation to the track rails 1, are mounted two receiving coils 20, having their windings connected in such a way that currents induced therein by currents flowing in opposite directions in the two track rails will be additive. These coils may or may not be mounted on laminated iron cores. When an alternating current flows in opposite directions in the track rails, a current will be induced in these coils in accordance with the laws of electro-magnetic induction.

65 The windings of the receiving coils 20 are connected to a main car relay MR through an amplifier A by means of a circuit which may be traced as follows:—From the receiving coils 20, wires 21 and 22, contact finger 23 of push button relay PR, wires 24, 25 and 26, input circuit of amplifier A, wires 27 and 28 back to the receiving coils 20; the amplified currents being carried to the main car relay MR by wires 29 and 30. A tuning condenser T is connected across the input circuit of the amplifier A as shown. The capacity of this condenser is of such a value that the input circuit will be tuned to the frequency of the train control current.

70 The amplifier A, conventionally illustrated in the drawings, is preferably of the type which acts to respond to weak current impulses in its input circuit and to produce more powerful currents in its output circuit. This amplifier may be of the vacuum tube type, although any other suitable type of amplifier 75 may be used.

75 A rotating shaft 31 is geared or otherwise driven from an axle of the vehicle, the connection of this shaft to the axle having been represented by a dot and dash line. Mounted on this shaft are a worm gear 32 and a centrifugal speed responsive device or centrifuge F. This centrifuge has been illustrated in a conventional form for the sake of simplicity, it being understood that any form of centrifuge 80 adapted to this type of system may be employed. The centrifuge F illustrated consists of a collar 33 fixed to the shaft 31 and a collar 34 which is movable on this shaft. These collars are urged apart by the coiled 85

spring 35. Two pairs of links 36, 37, 38 and 39, carrying the weights 40, are mounted between the collars 33 and 34. The collar 34 engages a lever 41 which is fixed on a speed shaft 42. It is apparent that as the speed of the vehicle increases, the weights 40 will be thrown outwardly, drawing the collar 34 down against the resistance of the spring 35, and thus rocking the speed shaft 42 through the lever 41.

The worm gear 32 engages a worm wheel 43 which is connected by the pinion 44 to a gear wheel 45. A pinion 46 is rotatably carried on a movable arm 47, this arm being journaled on the shaft of the gear wheel 45 in such a manner that the pinion 46 is in engagement with the gear wheel 45 regardless of the position of the arm 47. The arm 47 is normally held in the position shown by the cam starter magnet CS which draws this arm down against the pull of a spring 48.

Directly over and in line with the pinion 46 is a mutilated gear 49 fixedly secured to a distance shaft 50. The distance shaft 50 carries a special cam, 51, and a distance cam, 52. The cam 52 operates to open normally closed contact fingers 54 and 55 after a given distance of car travel from the point at which the distance shaft 50 is started by the de-energization of the cam starter magnet CS. The contact finger 54 is resilient, and is biased to be retracted from the stationary contact finger 55. The contact finger 54 carries an arm and a roller as shown, the roller bearing 35 against the edge of the distance cam 52 so that the contact fingers are normally maintained closed by this cam. A spring 56 is provided for normally holding the distance shaft 50 in the position shown, and for returning it to this position when the pinion 46 is disengaged from the mutilated gear 49. The purpose of the distance cam 52 and its associated contacts will become apparent as the description progresses.

The cam 51 is specially shaped and operates one end of a floating lever 57, the other end of which is moved by a lever 58 fixed to the speed shaft 42. It is evident that the movement of any intermediate point on the floating lever 57 will be dependent on a function of the speed of the vehicle and its distance of travel from the point at which the distance shaft 50 was started. A connecting rod 59 connects an intermediate point of the floating lever 57 to a cam 60. This cam is biased by a spring 61, and operates to open the normally closed contact fingers 62 similar to the contact fingers 54 and 55, under certain conditions of speed and of distance 55 of travel from a given point.

A push button PB operating a normally open movable contact 63, is preferably located in the cab of the vehicle, within easy access of the engineer or train operator. This push button operates when depressed to close a cir-

cuit through the push button relay PR, which is preferably mounted in an apparatus housing, carried on the tender or at any other convenient point on the vehicle. The circuit to the push button relay is obvious from the drawings.

A main car relay MR, a push button relay PR and a non-control relay NC are provided, and operate to make and break circuits for the car-carried apparatus as hereinafter described. These relays may be of any suitable type, and are provided with movable contact fingers which are biased by springs counter-weights or other means, so that the fingers move to a predetermined position when the relays are de-energized. The contact fingers of the main relay are preferably mounted on vertically arranged axes so that their motion will be unaffected by the vibration of the swaying of the train. The non-control relay NC is of the slow-acting type, that is, this relay is so constructed and arranged that it will not release its contacts immediately on the de-energization of its windings. The purpose of this slow-acting feature will be brought out in another part of the specification.

An electro-pneumatic valve EPV is provided, and may be of any suitable type adapted for train control practice. It is preferably of a type which, when de-energized, will act to effect a braking action on the train by directly venting the brake pipe pressure, by operating the usual engineer's brake valve or in any other suitable manner. As the specific type of electro-pneumatic valve used is immaterial, a conventional form of valve has been represented, and it will be understood that any other type of electro-pneumatic valve or brake control apparatus might be used without departing from the spirit of the invention.

The cab signals G and L are provided, being operated by a contact finger of the main relay MR. These cab signals may be of any suitable type and are preferably light signals, their indications being designated by colors, letters or by any other suitable means. All devices and controls have been shown in their normal position in the drawings.

Operation.—Assuming that a train is traveling over a block in which clear traffic conditions exist, that is, that no train is located in the block under consideration or in the next block in advance, the train control current flowing in opposite directions in the two track rails will induce currents in the receiving coils 20, which currents will be amplified by the amplifier A and impressed on the main relay MR. This will cause the main relay to maintain its contact fingers 66, 79 and 81 in the attracted position as shown, the contact finger 79 maintaining the high speed cab signal G in its indicating condition, and the contact finger 81 maintaining

an energizing circuit for the cam starter magnet CS, which circuit may be traced as follows:—From the battery terminal B, through contact finger 81 and front contact of the main relay MR, wire 82, contact finger 77 and back contact of the non-control relay NC, wire 83, winding of the cam starter magnet CS to the battery terminal C. For the sake of simplicity, the letters B and C have been used to represent the opposite poles of a source of electrical energy which may be the opposite terminals of a battery. With the cam starter magnet CS energized, the distance shaft 50 will be in its normal position as shown, and the contact fingers 54, 55 and 62 will be closed. The contact fingers 62 will maintain the electro-pneumatic valve EPV energized through a circuit which is obvious, and the train may proceed without restriction. The contact finger 76 of the non-control relay NC will be in its retracted position and the contact finger 79 of the main relay MR will be in its attracted position as shown, maintaining a circuit to, and so displaying, the high speed cab signal G, which circuit is obvious from the drawings.

The speed and distance cam 60 may be so arranged and constructed that its contacts 62 open if a maximum speed of, say, 60 miles per hour is exceeded. This opening of contact 62 de-energizes the electro-pneumatic valve EPV and causes an automatic brake application which remains in effect until the train speed is reduced below the maximum speed limit of 60 miles per hour.

Assuming that a train is located in block I, its wheels and axles will shunt the train control and signal currents from the rails in block I, de-energizing the track relay 7. This cuts off the train control current from the block H by releasing the track relay contact fingers 5 and 6. Now assuming that a second train enters the block H, its receiving coils 20 are not energized, and the main car relay MR will be de-energized, releasing its contact fingers 66, 79 and 81. The dropping of the contact finger 79 energizes the low speed cab signal L through a circuit which is clearly shown in the drawings, notifying the engineer or train operator that he is entering a caution or danger block. The releasing of the contact finger 81 de-energizes the cam starter magnet CS, causing the engagement of the pinion 46 with the mutilated gear 49, and the consequent movement of the distance shaft 50. This movement of the distance shaft 50 causes the special cam 51 to move the floating lever 57, thereby imposing more and more restrictive speed limits upon the train through the speed and distance cam 60, as the train progresses into the caution block. When the distance shaft 50 has turned through an angle of 180 degrees, the mutilated portion of the gear 49 is opposite the teeth of the pinion 46, and no

further rotation is imparted to the distance shaft 50. At this point the special cam 51 holds the floating lever 57 in its extreme low speed position, and the train may proceed only at a minimum speed of say, 15 miles per hour until traffic conditions ahead have become more favorable. The contact 54 of distance cam 52 is also opened but only after a certain distance of travel, assumed to be 500 feet. The purpose of this distance cam 75 with its associated contacts will become more apparent as the description progresses.

Now assuming that as the train under consideration progresses under the low speed restriction just described, the traffic conditions ahead become more favorable; that is, that the advance train passes out of the block I. The train control current now returns to the rails in the block H by the re-energization of the track relay 7. The receiving coils 20 pick up current from the rails and the main car relay MR is energized, lifting its contact fingers 66, 79 and 81. The lifting of contact finger 79 energizes the high speed cab signal G through a circuit which is obvious, informing the engineer or train operator that he may now proceed without further low speed restriction. The lifting of contact 81 re-energizes the cam starter magnet CS, disengaging pinion 46 from mutilated gear 49, and allowing spring 56 to return the distance shaft 50 to its normal position. This closes the contact fingers 54 and 55 of the distance cam 52 and allows the special cam 51 to return to the position shown in the drawings at which high speed restriction only is imposed.

It is obvious from the above description of the normal operation of the train control apparatus that the engineer is immediately informed when he enters a caution block, or when another dangerous condition, such as a train or a broken rail, exists either in the block in which he is located or in the next block in advance. It is also clear that the engineer is immediately informed when traffic conditions ahead become more favorable so that he may proceed at a higher speed.

Assume now that a train is progressing under clear traffic conditions in block I, which is the last block in a section of trackway equipped for automatic train control of the type under consideration. The engineer, by means of way side indications or from his knowledge of the trackway equipment, will find that he must set the car-carried train control apparatus to its inactive condition, as he is about to travel over a section of trackway which is unequipped for automatic train control. On entering the excess energy section J, the engineer depresses the push button PB. This completes a circuit to the push button relay PR, causing its contact fingers 23, 64 and 65 to be attracted. The opening of the back contact of finger 23

inserts a resistance R into the circuit from the receiving coils 21 to the main car relay MR. As a comparatively heavy current is flowing in the rails of the excess energy section J, this insertion of the resistance R into the circuit of the receiving coils does not diminish the amount of energy supplied to the main car relay MR, and this relay is maintained energized with its contact fingers in their normal positions as shown. The attracting of contact finger 64 of the push button relay PR closes a circuit to the non-control relay NC, which circuit may be traced as follows:—From the battery terminal B, through contact fingers 66 of the main relay MR, wire 67, contact finger 64 of the push button relay PR, wires 68 and 70, winding of the non-control relay NC to the battery terminal C. The energization of the non-control relay NC, causes its contact fingers 73, 75, 76 and 77 to be attracted. The non-control relay NC is of the slow acting type and maintains its contact fingers in their attracted positions for a short period after the contact finger 64 is released. The engineer immediately releases the push button PB, retracting the contact fingers 23, 64 and 65 of the push button relay PR. As the contact finger 65 is retracted, it closes a stick circuit to the non-control relay NC, which circuit may be traced as follows:—From the battery terminal B, through contact finger 65 of the push button relay PR, wire 71, contact fingers 54 and 55 of the distance cam 52, wire 72, contact finger 73 of the non-control relay NC, wires 74 and 70 and winding of non-control relay NC to the battery terminal C. The train may now proceed in non-control territory without further restriction for the reason that the contact finger 75 of the non-control relay NC is attracted, energizing the electro-pneumatic valve EPV through a circuit which is obvious from the drawings and thus preventing an automatic brake application. The contact finger 76 is also attracted, displaying the non-control cab signal 80 and thus informing the engineer or train operator that he may proceed in unequipped territory without train control restriction. The contact finger 77 of the non-control relay NC is in its attracted position and when the main car relay MR drops its contact finger 81, due to lack of train control current in block K, a circuit is completed to the cam starter magnet CS, maintaining this magnet energized and the distance shaft 50 in its normal position as shown. This circuit to the cam starter magnet CS may be traced as follows:—From the battery terminal B, through the back contact of finger 81 of the main relay MR, wire 82, front contact of finger 77 of the non-control relay NC, wire 83 and the winding of cam starter magnet CS to the battery terminal C.

When the push button PB is depressed and the non-control relay NC is energized as the train enters the excess energy section J, it will be observed that the cam starter magnet CS is de-energized for the reason that contact finger 77 of the non-control relay NC and contact finger 81 of the main relay MR are both in their attracted positions. The cams 51 and 52 will therefore be initiated and if the excess energy section were more than 500 feet in length, the cam 52 would open its contact fingers 54 and 55 so breaking the stick circuit to and de-energizing the non-control relay NC. In order to avoid this de-energization of the non-control relay, the excess energy section J is less than 500 feet in length.

When the train returns to a section of trackway which is equipped for automatic train control, the receiving coils 20 again have currents induced therein which act to energize the main car relay MR. This causes said relay to attract its contact fingers 66, 79 and 81. The closing of the front contact finger 81 causes the de-energization of the cam starter magnet CS and the rotation of the distance shaft 50. After the train has traveled a given distance, assumed to be 500 feet, the distance cam 52 opens its contact fingers 54 and 55, breaking the stick circuit to the non-control relay NC, which then retracts its contact fingers 73, 75, 76 and 77. When the contact finger 77 of the non-control relay is retracted, a circuit to the cam starter magnet CS through the contact finger 81 of the main car relay MR is again completed, this circuit being obvious from the drawings, and the distance shaft 50 is returned to its normal position. The car-carried train control apparatus is now in its active condition and the train may proceed in the equipped section of trackway under the restrictions imposed by the automatic train control system as described above. In order that the car-carried control apparatus may be set to its active condition when the train returns to equipped territory regardless of the condition of the first equipped block encountered, that is, regardless of whether or not there is train control current flowing in the track rails in this block; a short, permanently energized section of trackway may be provided at each point where the train passes from an unequipped to an equipped section of trackway. This permanently energized section of trackway will operate to re-energize the main relay MR, thereby de-energizing the cam starter magnet CS and breaking the stick circuit to the non-control relay NC, as described above.

On re-entering a section of trackway equipped for automatic train control, the engineer cannot avoid the restrictions of the car-carried train control apparatus by depressing the push button PB and thus maintaining the push button relay PR energized, as the en-

ergization of the non-control relay NC through its stick circuit is thus broken at contact finger 65 of relay PR, and the pick up circuit for relay NC is broken at contact finger 66 of relay MR, since with relay PR up, resistance R is in circuit with the relay MR, and such relay can pick up only with excess energy. Thus the relay NC drops at once, instead of being later dropped by member 52 as above described, so as to de-energize magnet CS and impose a restriction on the car. This prevents the abuse of the push button relay by the engineer or train operator to avoid the restriction of the automatic train control apparatus.

Now assume that a train is proceeding over a section of trackway unequipped for automatic train control, and that a stray trackway current is encountered, said trackway current arising from leakage or from any other cause. If such current flows through the track rails in multiple, the coils 20 are substantially unaffected, while if the flow is in series, the receiving coils 20 are immediately energized, causing the energization of the main relay MR and the attracting of its contact finger 81. This effects the de-energization of the cam starter magnet CS, starting the rotation of the distance shaft 50 and the distance cam 52. This will not however, cause an immediate de-energization of the non-control relay NC, for the reason that the distance cam 52 does not open its contact fingers 54 and 55 and so break the stick circuit to the non-control relay NC until after the train has traveled a given distance, assumed to be 500 feet, with its receiving coils 20 in their energized condition. On the assumption that these stray currents or transients which may be picked up in unequipped sections of trackway will be of short duration, the protection afforded by the distance cam 52 is adequate to carry the train across such temporarily energized sections without the de-energization of the non-control relay NC, and a subsequent automatic brake application. When the receiving coils 20 are no longer energized by these transient currents, the main car relay MR again drops its contact finger 81, and the cam starter magnet CS is re-energized, causing the return of the distance shaft 50 to its normal position.

It should be noted that the engineer or train operator cannot, in the present system, avoid the restrictions of automatic train control operation by depressing and fastening down the push button PB. When the train is traveling over a section of trackway equipped for automatic train control operation and push button PB is depressed, the insertion of the resistance R in the circuit of the receiving coils 20 will cut down the current received from the rails to such an extent that the main car relay MR will be de-energized, causing the de-energization of the cam starter

magnet CS, and thus imposing a low speed restriction. The elements of the main relay MR and the non-control relay NC are so designed and adjusted that the contact finger 66 of the main relay will open its front contact before the contact finger 73 of the non-control relay has closed its front contact, and, as a result, the stick circuit for the non-control relay may not be completed while the train is traveling in equipped territory.

Also, if the engineer attempts to prevent the relay MR from picking up upon re-entering train control territory, by picking up relay PR, thus to prevent starting speed restricting cam 60, the opening of contact 65 will drop relay NC to de-energize CS and thus require him to again release the push button PB in order to proceed unrestricted.

From the foregoing description it is seen that an automatic train control system has been provided in which control influences are continuously transmitted to the moving vehicle, and its progress along the trackway is regulated by car-carried apparatus controlled by said control influences. It is also seen that a simple and efficient means for effecting a change over from train control territory to sections of trackway unequipped for train control has been provided, together with means for preventing the abuse by the engineer or train operator of such change over apparatus. Further, it is evident that means have been provided to prevent unnecessary delay of train operation in territory unequipped for automatic train control, due to stray currents or transients existing in the rails in such unequipped territory.

It is to be understood that the present invention is not limited to the specific details described, and further, that many additions, modifications and changes could be made without departing from the spirit of the invention. For instance, means for operating the railway vehicle with either end leading could be provided, and automatic or manual switching means for said reversing apparatus could be used. Also, the main car relay could be of the polyphase type, imposing high, medium and low speed restrictions on the train instead of simply high and low speed restrictions, and many other modifications, combinations or additions might be made without departing from the spirit of the present invention.

What it is desired to secure by Letters Patent is:

1. In an automatic train control system for a railway having a portion of its trackway equipped for automatic train control and a portion not so equipped, the combination with car-carried brake control apparatus controlled from the trackway in equipped territory in accordance with traffic conditions ahead; of means rendering said apparatus ineffective while the train is travelling in un-

a railway having sections of its trackway equipped for automatic train control and other sections not so equipped, car-carried control means for controlling the brakes including a main car relay normally energized by influences continuously received from such equipped sections of trackway, a second relay adapted so long as energized to render said control means inactive, means for temporarily energizing said second relay as the train moves from an equipped section to an unequipped section of trackway, and means for maintaining said second relay energized after it has been once energized until said main car relay is energized throughout a given distance of train travel.

9. In an automatic train control system, car-carried apparatus for controlling the progress of a vehicle in response to influences corresponding to traffic conditions ahead including a main car relay and a distance operated cam, said cam being normally maintained in an initial position by the energization of a magnet, and a second relay for rendering said control apparatus inactive, said magnet being maintained energized when said main car relay is deenergized and said second relay is energized, said magnet being also maintained energized when said main car relay is energized and said second relay is deenergized.

10. In an automatic train control system for a railway having sections of its trackway equipped for automatic train control and sections not so equipped, car carried apparatus including a main car relay for controlling the brakes of a vehicle in response to influences transmitted from the trackway in said equipped sections, a second relay acting when energized, to render said control apparatus inactive, said second relay being held energized through a stick circuit when the vehicle is travelling over said unequipped sections; and a distance element, set into operation by the energization of said main car relay, for interrupting said stick circuit only after a certain distance of travel after said main car relay becomes energized.

11. In an automatic train control system, car carried apparatus including a car relay for controlling the brakes of a vehicle in accordance with influences corresponding to traffic conditions ahead, a second relay having a stick circuit, contacts in said stick circuit, and a distance measuring device adapted to be driven from the car wheels for opening said contacts only after a predetermined distance of travel, said device being set into operation by the energization of said car relay.

12. In an automatic train control system for a railway having a section of its trackway equipped for automatic train control and portions not so equipped, car-carried apparatus for controlling the brakes of a vehicle

in accordance with influences corresponding to traffic conditions ahead, a relay for rendering said control apparatus inactive having a stick circuit and a pick up circuit, said stick circuit including contacts of a circuit controller, which contacts are closed only when said circuit controller is in its non-operating condition, a main car relay energized on the entrance of the vehicle into said equipped sections of trackway, and other contacts for said stick circuit which are opened only after a predetermined distance of vehicle travel from the point at which said main car relay is energized.

13. In an automatic train control system, car-carried brake control apparatus including a main car relay, a distance element initiated by the de-energization of an electromagnet, two energizing circuits for said electro-magnet including respectively a front contact and a back contact of said main car relay and a non-control means for maintaining said brake control apparatus inactive until said distance element has operated for a given distance of car travel; said non-control means selectively controlling said energizing circuits.

14. In an automatic train control system, car-carried brake control apparatus including a main car relay, a non-control relay having a stick circuit, and means opening said stick circuit after a given distance of travel upon the energization of said main car relay.

15. In a train control system, car-carried apparatus including, a car relay controlled in accordance with trackway conditions, train control means controlled by the car relay, a non-control relay for removing the train control means from control by said car relay, a pick up circuit for the non-control relay including a normally open manually operated contact and a front point of the car relay, and a stick circuit for the non-control relay including a normally closed manually operated contact, and a distance operated contact.

16. In a train control system, car-carried apparatus including, a car relay controlled in accordance with trackway conditions, train control means controlled by the car relay, a non-control relay for removing the train control means from control by said car relay, a pick up circuit for the non-control relay including a normal open manually operated contact and a front point of the car relay, a stick circuit for the non-control relay including a normally closed manually operated contact and a distance operated contact, and traffic controlled means for initiating the distance operated contact.

17. In an automatic train control system, car-carried train control means including, a main relay, a non-control relay, an energizing circuit for the non-control relay, and contact means for changing the condition of such cir-

equipped territory comprising, an energizing circuit for rendering said means active, and a manually controllable normally open circuit controller for controlling said energizing circuit, said means being inactive in unequipped territory unless said circuit controller is in its normal open position.

2. In an automatic train control system for a railway having a portion of its trackway equipped for automatic train control and a portion not so equipped, means for controlling the movement of a vehicle in equipped territory in accordance with traffic conditions ahead including brake control apparatus, receiving coils, amplifying means, and an electro-responsive device cooperating with a trackway circuit which supplies energy to the receiving coils continuously except under unfavorable traffic conditions; means for maintaining said brake control apparatus inactive while the train is travelling in unequipped territory comprising, a normally deenergized relay, an energizing circuit for said relay including a contact closed only if said electro-responsive device is energized and a normally open contact of a manually controllable circuit controller, said circuit controller when operated rendering the receiving coils, amplifying means and electro-responsive device incapable of maintaining said contact of the electro-responsive device closed in response to the largest amount of current flowing in said trackway circuit in equipped territory, a trackway circuit at the entrance to an unequipped section of trackway and supplied with an excessive amount of current sufficient to maintain closed the contacts of the electro-responsive device with said circuit controller in its operated position, said relay being deenergized when the vehicle is travelling in unequipped territory unless said circuit controller is restored.

3. In an automatic train control system for a railway having a portion of its trackway equipped for automatic train control and a portion not so equipped, the combination with car-carried brake control apparatus controlled from the trackway in accordance with traffic conditions ahead, of means rendering said apparatus ineffective while the train is travelling in unequipped territory comprising, a manually operable circuit controller, a stick relay which when energized will render said apparatus ineffective, a pick up circuit and a stick circuit for said stick relay, said stick circuit including a contact closed only when said manually operable circuit controller is in its normal position.

4. In an automatic train control system for a railway having a portion of its trackway equipped for automatic train control and a portion not so equipped, car-carried brake control apparatus continuously controlled by energy received from the trackway through a tuned receiving circuit, means for render-

ing said brake control apparatus inactive while the train is travelling in unequipped territory comprising, a manually operable circuit controller, a resistance inserted in said tuned receiving circuit by the operation of said circuit controller, a relay initially energized by said circuit controller and maintained energized by the release of said circuit controller, said relay operating when energized to render said brake controlling apparatus inactive provided sufficient energy is supplied to said receiving circuit to counteract the effect of said resistance, and an insulated section of track rails adjacent to said unequipped portion of trackway, supplied with an excess amount of energy, thereby supplying said sufficient amount of energy to said receiving circuit.

5. In an automatic train control system for a railway having a portion of its trackway equipped for automatic train control and a portion not so equipped, car-carried brake control apparatus continuously controlled by energy received from the trackway through receiving equipment, a manually operable device acting when operated to reduce the sensitivity of said receiving equipment, means at the entrance to such unequipped portion of trackway for delivering an excessive amount of energy to said receiving equipment, and means for maintaining said brake control apparatus inactive while travelling in the unequipped portion of trackway, said last mentioned means being initially actuated by operation of said manually operable device and being held actuated only if said device is in its normal non-operated condition.

6. In an automatic train control system for a railway having a portion of its trackway equipped for automatic train control and a portion not so equipped, car-carried apparatus for automatically controlling the movement of a train in accordance with control influences corresponding to traffic conditions ahead, a non-control device for rendering said automatic control means inactive when the train is travelling in said unequipped territory, and means for rendering ineffective said non-control device upon the return of the vehicle to equipped territory only after a given distance of vehicle travel.

7. In an automatic train control system for a railway having a portion of its trackway equipped for automatic train control and a portion not so equipped, car-carried apparatus for controlling the movement of a train in said equipped territory comprising a distance element, a relay for maintaining said car-carried control apparatus inactive when the train is travelling in said unequipped territory, and means including said distance element for rendering said relay ineffective only after a given distance of travel in said equipped territory.

8. In an automatic train control system for

cuit after a given distance of travel upon the energization of said main relay.

18. In an automatic train control system, car-carried train control means including, a main relay, a non-control relay, an energizing circuit for the non-control relay, and means opening such circuit after a given distance of travel upon the energization of said main relay.

19. Railway vehicle carried apparatus comprising a circuit receiving energy from the trackway and including a normally shunted resistance, a main relay controlled by said circuit and responsive to the energy normally received therein when said resistance is shunted but not responsive when the shunt around the resistance is removed unless the circuit receives a greater amount of energy from the trackway, a cut-out relay, a pick-up circuit for said cut-out relay including a normally open circuit controller and a contact closed only when said main relay is energized, a stick circuit for said cut-out relay including a contact controlled by the energization of said main relay, and manually operable means for simultaneously opening the shunt around said resistance and closing said normally open circuit controller.

20. In an automatic train control system, car-carried control apparatus including a normally deenergized stick relay, a manually controllable circuit controller having a normally open contact and a normally closed contact, a pick up circuit for said stick relay including said normally open contact, and a stick circuit for said stick relay including said normally closed contact.

21. In a train control system, car-carried apparatus including, a car relay controlled in accordance with trackway conditions, train control means controlled by the car relay, a non-control relay for moving the train control means from control by said car relay, a pick up circuit for the non-control relay including a normally open manually controlled contact and a front point of the car relay, and a stick circuit for the non-control relay including a normally closed manually controlled contact.

22. Railway vehicle carried apparatus comprising a circuit receiving energy from the trackway, a circuit controller having a normal position and manually controllable to a reverse position, a main relay controlled by said circuit and responsive to the energy normally received therein if said circuit controller is in normal position but not responsive when said circuit controller is in reverse position unless the circuit receives a great amount of energy from the trackway, a cut-out relay, a pick-up circuit for said cut-out relay closed only when said main relay is energized and said circuit controller is in reverse position, a stick circuit for said cut-out relay effective only when the cut-out

relay is energized and said circuit controller is in normal position, vehicle governing mechanism controlled by said main relay, and means for removing said mechanism from control by said main relay when said cut-out relay is energized.

23. Railway traffic controlling apparatus comprising, a main relay controlled from the trackway, a controller having a normal position and manually controllable to a reverse position, a cut-out relay, a pick-up circuit for said cut-out relay closed only when said main relay is energized and said circuit controller is in reverse position, a stick circuit for said cut-out relay effective only when the cut-out relay is energized and said circuit controller is in normal position, vehicle governing mechanism controlled by said main relay, and means for removing said mechanism from control by said main relay when said cut-out relay is energized.

In testimony whereof I affix my signature.

CHARLES S. BUSHNELL.
